UNITED STATES PATENT OFFICE

ARLINGTON MOORE, OF NEW YORK, N. Y., ASSIGNOR, BY MESNE ASSIGNMENTS, TO
MAXMOOR CORPORATION, OF NEW YORK, N. Y., A CORPORATION OF DELAWARE
CHARGE-MODIFYING APPARATUS FOR INTERNAL-COMBUSTION ENGINES

Application filed June 28, 1926. Serial No. 118,963.

My invention is of a charge modifying apparatus arranged to form a portion of a bypass conduit connecting the exhaust passage of an internal combustion engine with the intake passage above the carburetor and engine throttle, and constructed and arranged to effect delivery, into admixture with the fuel and air mixture from the carburetor in the intake passage, of air and exhaust gas of the engine, in proportions and quantities and at temperatures automatically regulated in consonance with the movement of the engine throttle to correct defects in the formation and distribution of the fuel and air mixture supplied by the carburetor and the burning thereof in the engine cylinder under the various conditions of engine speed and torque.

This application is in part a continuation of my copending application Serial No. 26,265, filed April 27, 1925.

The invention will be best understood from the following description of illustrative embodiments thereof, which are shown in the accompanying drawings in which Fig. 1 is a partly sectional view of an internal combustion engine equipped with a charge modifying device in accordance with my invention. Fig. 2 is a view similar to a portion of Fig. 1 and showing modified means for air admission and modified means for admixture of the charge modifying gases with the fuel and air mixture supplied by the carburetor. Fig. 3 is a section on line 3—3, Fig. 2. Figs. 4, 5 and 6 are detail views showing respectively positions of poppet valve of Fig. 2 for idling, for partial throttle opening, and at or toward wide open throttle. Fig. 7 is a longitudinal sectional view of the charge modifying device with modified means for admitting atmospheric air comprising a slide valve. Fig. 8 is a section on line 8—8, Fig. 7. Fig. 9 is a partly diagrammatical view showing the positions of air slide valve of Fig. 8 and other parts of the apparatus for partial throttle opening. Fig. 10 is a view similar to Fig. 9 and showing the position of the parts for full throttle opening, and Fig. 11 is an enlarged detail view of the valve operating cam sector.

Reference character 10 designates a cyl-

inder of a multi-cylinder internal combustion engine. The dotted lines in Fig. 1 indicate the cylinder head position of common standard practice with a compression ratio of about 4½:1, while the full lines show the cylinder head machined off and lowered to obtain a high compression ratio, which is in excess of 5:1, and is preferably 6:1 or more. Low compression engines can be converted to high compression engines in other ways, as by use of longer connecting rods, or, of course, the engines may be constructed with any desired compression ratio. Internal combustion engines with such high compression ratios detonate violently when using ordinary gasoline, for example, as fuel, but are free from such detonation when provided with my conversion device. Reference numeral 11 indicates the exhaust manifold, 12 the intake manifold, 13 the carburetor, and 14 the throttle valve.

The charge modifying apparatus 15, which is connected to the exhaust conduit, preferably about opposite the back cylinder, and is also connected to the intake above the throttle, contains the heater 16 of good heat conducting material, preferably copper, cast iron or the like. An impact tube 17 is provided for supplying the exhaust gases from the exhaust manifold 11 to the chamber 18 in heater 16 without substantial loss of kinetic energy. The impact tube 17 is of substantially elbow form and as shown is screwed into the exhaust manifold 11 and constitutes the means for connecting device 15 to the exhaust manifold. The impact of exhaust gases entering the inlet passage 19, directed upstream against the gas flow in the exhaust conduit, ensures effective delivery of exhaust gas to the charge modifying device and engine intake, with practically no loss of the kinetic energy of the exhaust gases moving in the exhaust manifold.

The impact tube member 17 has a separate outlet passage 20 directed downstream of the gas flow in the exhaust manifold. By directing inlet 19 upstream and outlet 20 downstream I ensure effective circulation of a very substantial proportion of the entire hot exhaust gas of the entire through the chamber

18 in heater 16, and back into the exhaust conduit, and secure a highly effective heating action of the heater 16.

A port 30 is provided in the wall of the stove or heater 16 at a point adjacent to the outlet 20. Said port 30 is for the passage of gases going to the engine intake, and said port is controlled by valve 32. Chamber 18 in heater 16 is provided with a lengthwise extending partition or baffle 26, over or beyond which the exhaust gases pass after admission through the impact tube, and usually are sent at least in part back into the exhaust manifold at the outlet 20. In this way, whether the gases pass back to the exhaust gas conduit or out through the port 30, they contact with and give up heat to substantially all parts of wall or lining of the heater.

Hot air from off the hot exhaust pipe 11 enters the air inlet 34 between the casing 36 of the device 15 and the inserted shell 38, which shell 38 is formed with longitudinal ribs 39 providing the up and down air passages 40, 42, 44 and 46. Up passage 40 communicates through down passages 42 with up passages 44, and these with down passage 46, the last named passage 46 leading to air port 48. Port 48 is controlled by air valve 50 and also at certain times by the valve 32, which controls the exhaust gas port 30. Stem 52 of valve 32 works in the bore 54 of air valve 50, and both ports 30 and 48, for exhaust gas and heated air respectively, lead into the mixing chamber 56 between the heater 16 and shell 38, and such gaseous materials after being thoroughly mixed and their temperature averaged by mixing, and being further heated by contact with the heat conducting ribs 58 on stove 16, are delivered at 60 to the quantity control valve 62, preferably a poppet valve, and after passing valve 62 (or the needle valve 64) are delivered by tube 66 to the intake manifold 12, preferably just over the butterfly throttle valve 14.

45 The delivery from pipe 66 to the intake passage is preferably in the direction of the air and fuel stream flow and in generally injector fashion. For example, the delivery may be effected through the centrally located outlet 68 of curved pipe 70, directed in the direction of inlet gas flow, as shown in Fig. 1, or the hot gases from the charge modifying device may be delivered around and out beyond the end of the funnel or injector 72, 55 also in the direction of flow in the intake, as shown in Fig. 2.

Valves 32, 50 and 62 are operated by the cam sector 74, valve 62 being actuated through its stem 76 by means of the cam portion 78 of said member 74, and air valve 50 by the coaction of the teeth 80 of member 74 with the rack teeth 82 of said valve 50. The exhaust gas valve 32 is actuated from member 74 through the intermediation of the air valve 50. Said valve 32 is held toward port

30 by spring 84, interposed between the stem 52 of valve 32 and the fixed bracket 86 which is secured to the valve barrel 88, made integral with or attached to casing 36. Said valve 32 is opened by being moved against spring 84 by the valve 50 contacting with the adjustable lock nuts 90 on the threaded stem 52 of valve 32. As is apparent from Fig. 7, this is a lost motion connection, valve 50 opening first, and valve 32 remaining closed until valve 50 opens port 48 and its opposite end comes into contact with and moves valve 32 by making contact with the adjacent lock nut 90 attached to the stem of valve 32. (Figs. 9 and 10). The cleaning pin 92, adjustably clamped in bracket 86 extends through the bore 94 of valve 32 and serves to keep the bore 94 of valve 32 clean of foreign matter and also serves to regulate the bleeding passage 96 for exhaust gas into the mixing chamber 56. (Fig. 7.)

The needle valve 64 for idling has its port 98 formed in the poppet valve 62. This secures several important advantages, first that the port 98 is closed as soon as valve 62 is substantially opened so that, for further openings of valve 62 the passage of the charge modifying device gases is only, or practically only, past the seat of valve 62 and port 98 is substantially shut off, making possible a close regulation of valve 62, and making it unnecessary to regulate valve 62 in connection with any auxiliary passage, such as an open port 98, and second, the needle valve 64 in port 98 is made self-clearing in the same way as cleaning of bore 94 of valve 32 by pin 92 is automatically obtained. The needle valve 64 is preferably provided with a relatively long, gradually tapering point so as to remain in port 98 even when valve 62 is closed, and valve 62, being free to turn, except as restrained by needle valve 64, is guided and kept from turning thereby, as the former is opened or closed.

The cam member 74 is actuated automatically with the throttle 14, the crank arms thereof being preferably connected by linkage, as, for example, the link 99, which may be adjustably connected at either or both of the crank arms.

The hot mixture of air and exhaust gas, which is admitted above the throttle through the charge modifying device at partial throttle openings, is mingled directly with the charge, and the atomized fuel mixture delivered by the carburetor is completely vaporized and the temperature of the fuel mixture is materially raised.

It will be observed that the cam member 74 has a first acting cam portion 100 which opens valve 62 to a moderate extent (Fig. 9) and that the adjacent and following lower or recessed portion 102 of cam surface 78, which comes into coaction with valve stem 76 upon opening the throttle somewhat wider, 130

is of a form to permit a partial closing of valve 62 when it comes into action. This is because of the fact that when an automobile, for example, having its engine provided with a carburetor intended and constructed to itself supply all the elements of the charge without subsequent additions and without provision for inlet of gases above the throttle, is equipped with the charge modifying device, and is operated at high speed and with the throttle opened to about the extent corresponding to engagement of cam portion 102 with valve stem 76, with a relatively high vacuum above the throttle because of the high engine speed, if the poppet quantity valve 62 is opened too much, starving of the mixture will result, particularly in the case of the carburetor supplying a substantial maximum economy fuel ratio, by getting too much heated air above the throttle because of the high suction produced by the high engine speed, or, stated reversely, too little fuel, because of a substantial reduction in the quantity of air passing the fuel jet of the carburetor. The low spot or notch 102 in cam member 74 serves to permit valve 62 to close somewhat under these conditions and to prevent starving of the mixture. While relatively less economy is obtained with this arrangement at such throttle and poppet valve openings in case the engine is running slowly under load, this is negligible, at least in automobile practice, since running under these conditions is of relatively seldom occurrence, and when it does occasionally happen, a good power mixture is desirable.

At and toward open throttle position, the hot air port 48 is closed by valve 32, and port 30 for exhaust gas is wide open; also poppet control valve 62 is wide open, being actuated by the high portion 104 of cam face 78. See Fig. 10. The exhaust gas supplied in this way effectively prevents engine detonation. The various adjustments should be regulated to give enough exhaust gas in addition to the unscavenged gas remaining in the cylinders to prevent detonation, but not enough to cause power losses by undue dilution.

Cold air can advantageously be admitted with the exhaust gas used for preventing detonation at and toward open throttle, and means are provided for admission therewith of air, preferably atmospheric air. The cooling effect of such atmospheric air upon the hot exhaust gas at such times is of advantage, since additional heat is supplied to the charge by increased compression pressure, and the introduction of additional heat units is preferably to be avoided because of resulting charge rarefaction, reduction of initial pressure and loss of volumetric efficiency.

I have shown two modes of supplying cold atmospheric air at or near wide open throttle. In the form of Figs. 7, 8, 9 and 10, within the outlet well 61 below valve 62, which well is

transversed by the stem 76 of valve 62, said stem 76 has the slide valve 106 secured thereto above the outlet tube 66 by means of the cross-bar 108, leaving gas passages therethrough at 110, 110. The slide valve 106 controls an air inlet passage 112 to admit cold air. Said inlet passage 112 is arranged so that the incoming air travels in the direction of gas flow toward the engine intake. For example, said passage 112 may be arranged on a downward and inward incline, as shown in Figs. 7, 9 and 10. With such arrangement the exhaust gas passing through the slide valve ports 110 serves to a substantial extent for injecting the cold air therewith, and such effect is supplemented by delivering the gases to the intake in the direction of stream flow therein, as by means of the nozzle 70.

Air inlet 112 is open only when the valve 62 is actuated by cam portion 104, that is to say at or toward wide open throttle positions, or at positions of the throttle where detonation would occur in an engine not equipped with the charge modifying device, and said inlet 112 serves to admit air in metered quantities to admix with and cool the hot exhaust gas passing to the intake through pipe 66. With such arrangement the heat of the exhaust gases is materially tempered or lowered before commingling with the fuel-air mixture delivered by the carburetor, thus providing a full cylinder charge and preventing loss of volumetric efficiency through undue rarefaction of the charge by heat of the exhaust gas supplied.

An alternative mode is to first deliver the heated exhaust gas separately to the mixture supplied by the carburetor, and then after the resulting effective vaporization is secured, to separately supply as much cold air as the engine will take without resulting undue leaness of charge, making the delivery thereof preferably just before the intake manifold branches for entering the engine cylinders. Means for securing this desirable result are illustrated in Figs. 2, 4, 5 and 6, wherein poppet valve stem 76 is extended and provided with the poppet air valve 120 suitably supported on shoulder 122 and serving to admit atmospheric air at 123 to the intake manifold 12 through the tube 130 from the well 132 under valve 120. Poppet valve 120 is made adjustable, preferably by inserting shim washers 124 thereunder. In case cold air is not wanted, all the thin washers may be removed so that valve 120 will not be raised from its seat.

In addition to the leaf spring 125 for returning valve 62 to its seat, a second leaf spring 126 is held by bolt 128, and said spring 126 is apertured for the passage of stem part 76' and serves for returning valve 120 to its seat. Said air valve 120 is closed, except at times when the throttle is at or near its wide

open position, as appears from the detail showing in Figs. 4, 5 and 6. It will be seen that such arrangement provides for first thoroughly vaporizing the atomized mixture of fuel and air, delivered by the carburetor at and toward open throttle position, by means of exhaust gas delivered through the pipe 66, and that not until this is done are the additional parts of cold air supplied, and the cooling action resulting therefrom obtained.

Since the fuel is thoroughly vaporized by direct admixture therewith of heated gases, high velocity in the intake passage is not essential for purposes of breaking up or atomizing the fuel and I have, therefore, found it useful to provide an expansion chamber of relatively large diameter, such as shown at 136, Fig. 2, in which the speed of the mixture stream is reduced and thorough vaporizing is secured, and such expansion chamber may be supplied as an attachment between the carburetor and intake manifold flange or can be made a part of either the carburetor or intake manifold parts, if so desired.

It is of advantage to make the working parts of the apparatus of rustless, heat resisting material.

It will be seen that an internal combustion engine equipped with my apparatus has numerous features of advantage. In addition to such features already referred to, no specially constructed, high-velocity intake passages, with abrupt changes in direction, need be used, but the passages may be of generous dimension, smoothly rounded, and through which the gases of uniform composition flow readily and at low speeds without friction; loading up of the intake passages and cylinders with liquid fuel is avoided, crankcase dilution is eliminated, smoothness of engine operation and reduction of noticeable torque reaction of automobile engines is obtained, the dangerous carbon monoxide is eliminated from the exhaust, it is unnecessary to change carburetor adjustments from rich in winter to lean in summer and vice versa, and numerous other advantages are secured, among which it is particularly to be noted that with my charge modifying device high pressure engines are run on ordinary gasoline without detonation, using substantially maximum economy fuel mixtures.

I claim:

1. In an internal combustion engine, carburetor means for supplying a mixture of fuel and air to the engine, means communicating with said first-named means for supplying hot exhaust gas into admixture with the fuel and air stream from the carburetor, and means for separately supplying further air into the mixture.

2. In an internal combustion engine, a carburetor means above the carburetor for supplying hot exhaust gas into admixture with

the fuel and air stream from the carburetor, and means for separately supplying further cold air into the mixture.

3. In an internal combustion engine, means for supplying hot gases into admixture with the fuel-air stream from the carburetor substantially directly after passing the throttle, and means for supplying air into the mixture at a point further on in the direction of intake gas flow.

4. In an internal combustion engine, means for supplying hot gases into admixture with the fuel-air stream from the carburetor substantially directly after passing the throttle, and means for supplying cold air into the mixture at a point further on in the direction of intake gas flow.

5. Means for mixing exhaust gas and air, means for heating the mixture, and means for introducing such mixture into the intake of an internal combustion engine through an opening which is decreased at a predetermined opening of the throttle as compared with its extent of opening for both smaller and greater openings of the throttle.

6. In an internal combustion engine, means for admitting hot gases to the engine intake above the throttle, and means for admitting cold air to the engine intake at a point still nearer to the engine cylinders when and only when the throttle is at or near its wide open position.

7. In an internal combustion engine, a bypass conduit from exhaust to intake, valved proportioning means to admit exhaust gas and air to said conduit, valved means for controlling the quantity of such gases passing to the intake, a port for passage of gases to the intake at idling positions of the throttle, and means for closing said port at widened throttle openings beyond that for idling.

8. In an internal combustion engine, a chambered member, conduit means for connecting same in communication with the exhaust conduit and with the intake conduit over the throttle, valved means for proportioning exhaust gas and hot air admitted to the chamber in said casing, and valved means for controlling the quantity of such admixed gases admitted to the intake, and comprising a poppet valve with a port formed therein and an adjustable needle valve coacting with said port.

9. In an internal combustion engine, a conduit discharging into the intake in gas flow direction, valved means for mixing hot air and exhaust gas in predetermined proportions for delivery to said bypass and thence to the intake, and valved quantity determining means in said bypass comprising a poppet valve having a port formed therein and an adjustable needle valve coacting with said port.

10. In an internal combustion engine, a chambered member, conduit means for connecting same in communication with the ex-

haust conduit and with the intake conduit over the throttle, valved means for proportioning exhaust gas and hot air admitted to the chamber in said member, valved means for controlling the quantity of such admixed gases admitted to the intake and comprising a poppet valve with a port formed therein and an adjustable needle valve coacting with said port, and means for admitting cold air to the intake at a point between the cylinders and the point of connection of said conduit with the intake.

11. In an internal combustion engine, a pipe to the intake over the throttle, a chambered member in communication with said pipe, means for admitting hot air and exhaust air and exhaust gas to the chamber in said member, and means for controlling passage of such gases through said pipe comprising a valve having an opening therethrough when seated, and means for closing said opening when the valve is moved off its seat.

12. Apparatus for modifying the fuel and air mixture delivered from the carburetor of an internal combustion engine, comprising a chambered heater having inlet means directed upstream of the exhaust conduit and outlet means directed downstream of the exhaust conduit, a casing providing an annular mixing and heating chamber about the heater walls, valved means for admitting into said mixing chamber exhaust gas from the heater and hot air, and a conduit leading from said mixing chamber to the engine intake over the throttle.

13. In an internal combustion engine, means for supplying exhaust gas and air to the engine intake over the throttle, and means for heating same in the course of travel, comprising a heater through which is passed the exhaust gas supplied to the intake and also additional quantities of exhaust gas, which last named quantities of exhaust gas after giving up heat are returned to the exhaust conduit.

14. A chambered heater having a septum in the chamber with an opening therethrough, exhaust gas supply means directed against the flow of exhaust gas in the exhaust conduit in communication with the space in the heater chamber on one side of the septum, exhaust gas outlet means in communication with the space on the other side of the septum directed in the direction of flow of gas in the exhaust conduit, a valved port provided in the heater wall substantially adjacent to the outlet and on the same side of the septum as the outlet, and means for causing exhaust gas passing through said port and air to pass in a tortuous path about the heater walls and thence to the intake over the throttle.

15. In an internal combustion engine, means for providing a mixture of exhaust gas and air, and means interconnected with the throttle to automatically admit such mixture

to the intake over the throttle and arranged so that passage of such mixture is partially shut off at a stage intermediate between stages of wider opening.

16. In an internal combustion engine, means for admixing exhaust gas and air and for heating the mixture, and means interconnected with the throttle for delivering said mixture to the intake over the throttle and arranged to automatically reduce the quantity of gases so delivered at a predetermined throttle position below the quantity delivered at lower and wider openings of the throttle.

17. In an internal combustion engine, means for admitting exhaust gas and air to the engine intake over the throttle, said means comprising a valve and a cam for operating the valve, the cam having a recessed portion in its working part, whereby the valve is given a reduced opening between stages of wider opening.

18. In an internal combustion engine, a conduit for exhaust gas and air leading to the intake over the throttle, a poppet valve for controlling the quantity of gases passing through said conduit, a cam for operating said valve, said cam being interconnected to move with the throttle, means for shutting off the air admitted with the exhaust gas when the throttle is at or near its wide open position, and means operable with the shutting off of the air admitted with the exhaust gas to admit cold air to the intake at a point between the engine cylinders and the point of connection of said conduit to the intake.

19. In an internal combustion engine, a casing having air passages, a hollow heater in the casing with a mixing chamber therearound, said heater having a port in its wall leading into said mixing chamber, said mixing chamber having an outlet into the engine intake over the throttle, means for delivering exhaust gas to the heater and in part back to the exhaust gas conduit, and in part through said port in the heater wall, a port provided from the air passage to the mixing chamber, valves for said air and exhaust gas ports, the air valve having rack teeth, a rotary toothed member for actuating said air valve, and lost motion connecting means for actuating the exhaust gas valve from the air valve.

20. In an internal combustion engine, a conduit to the intake over the throttle, a second conduit to the intake between the first one and the engine cylinders, means for supplying exhaust gas through the first named conduit, means for supplying cold air through the second named conduit, and common actuating means for said two supply means.

21. In an internal combustion engine, including exhaust, intake and throttle, a bypass conduit from exhaust to intake over the throttle comprising a chambered heater, and means for circulating exhaust gas through the heater and back to the exhaust conduit.

22. In an internal combustion engine, including exhaust, intake and throttle, a bypass conduit from exhaust to intake over the throttle, means for circulating exhaust gas out of said exhaust and back into it for heating air, and means for introducing said air into the bypass conduit.

5
In testimony whereof, I have signed my name hereto.
